UNITED STATES PATENT OFFICE.

RUGELEY D. SEYMOUR, OF DENVER, COLORADO.

GRIP MECHANISM FOR CABLE-TRAMWAYS.

No. 913,775.

Specification of Letters Patent. Patented March 2, 1909.

Application filed December 18, 1908. Serial No. 468,159.

To all whom it may concern:

Be it known that I, RUGELEY D. SEYMOUR, a citizen of the United States, residing at Denver, in the county of Denver and State of Colorado, have invented a certain new and useful Improvement in Grip Mechanism for Cable-Tramways, of which the following is a specification.

This invention relates to gripping mechanism for attaching a load or loads to the moving traction rope of an aerial or wire rope tramway.

The object of the invention is to provide a very compact, unitary mechanism which may be readily attached to the car adjacent to the traction rope in such a way that it readily adjusts itself to different angular positions of the rope at different points on its course of travel.

20 A further object of the invention is to provide such a mechanism which will readily accommodate itself to different sizes of rope and different sized portions of the same rope.

The invention consists in a unitary structure capable of accomplishing the foregoing object which can be easily and cheaply made and installed which is positive and efficient in operation and not readily liable to get out of order.

30 It further consists in combinations and arrangement of parts which will be hereafter more fully described and claimed as the specification proceeds.

Referring to the drawings, Figure 1 shows 35 a side view of the device with the jaws open to receive the traction rope. Fig. 2 is a rear view with all the parts in the same position. Fig. 3 is a section through the center on the line *a* shown in Fig. 2. Fig. 4 is a front view 40 of the device with all parts in the same position as in Figs. 1 and 2. Fig. 5 shows a tramway bucket 28 with bail 27 hanger 23 and carriage 20 complete and shows the application and location of the gripping device in 45 the complete tramway.

For convenience in readily finding descriptions of the parts they will first be described in their numerical order, the numerals indicating as follows: 1—a circular frame preferably of cast iron or steel on which the moving parts are mounted. 2—the upper gripping jaw. 3—the lower gripping jaw. 4—an operating lever connected to the lower jaw 3 and to the links 5. 5—6—a pin or pivot for the operating lever 4.

7—a pin connecting the operating lever 4 and links 5. 8—cast extensions on the main frame 1 with recessed chambers therein. 9—a U shaped bolt passing through these chambers and engaging the upper jaw 60 2. 10—brackets upon the main frame. 11—lugs cast upon the front face of the main frame 1 and extending to the sides thereof as shown. 12—a flange or collar at the rear of the main frame 1. 13—a pin on 65 which a spring is mounted. 14—a pin for the jaws 2 and 3 mounted in the brackets 10. 15—an extension on the main frame 1 forming a recess in which the links 5 and lower jaw 3 operate as shown in Fig. 3. 16—a 70 roller upon the end of the operating lever. 17—nuts on the ends of the U shaped bolt 9. 18—a coiled spring wound about the post 13 and engaging the lower jaw 3. 19—coiled springs mounted upon the U shaped bolt 9. 75 20—an ordinary tram way carriage mounted on wheels 21 rolling on track 22. 23—a hanger for the rod carried by the pin 24 upon the carriage 20. 25—slots in the hanger 23 adapted to have the lugs 11 pass 80 therethrough. 26—a traction rope upon which the gripping jaws are used. 27—the bail of the bucket 28 in which the load is carried.

Numerals bearing the prime mark indicate the same parts as those without said mark but in a different position.

Taking up first the gripping mechanism;— The upper gripping jaw 2 is pivoted at 14 and has its operative arm 2^a engaged by the 90 compression springs 19 and the U bolt 9 with the result that when viewed as in Figs. 1 and 3 the jaw is normally pressed in a counterclockwise direction by said springs but may when properly energized move in 95 the opposite direction against the action of said springs. The tension of these springs may be varied by adjusting the nut 17. The opposite jaw 3 is also pivoted upon the same shaft 14 and has its operative arm 3^a 100 connected by a link 5 to the lever 4. This lever is adapted to swing between the dotted line and full line positions of Fig. 3 or between open and closed positions of the gripping jaws. The device is so mounted that 105 the roller 16 upon the lever 14 engages one of the ordinary tripping devices of a wire rope transmission system to automatically move it from either one of these positions to the other as required in the operation of 110

the device. When the parts are in full line position the jaws are absolutely locked because the pivotal points of connection between the lever 2 and the lever 3 are in line with each other and the pivotal point 6 of the lever 4, and therefore the jaw can only be moved by applying a force sufficient to move the lever 4 upward from its full line position. When the parts are thus gripped upon a rope any variation in the size of the rope is readily taken care of by the yielding action of the spring 19, said spring yielding to the movement of the jaw 2 when a very large rope is between the jaws and pressing said jaw hard against the rope even when a smaller rope is used and these adjustments take place automatically if it is attempted to use these jaws upon different portions of a rope having portions varying in size. It will thus be seen that the device is automatically adjustable for taking care of different sized ropes this in combination with automatic locking which holds the jaws rigidly in position. In order to assist the jaws in releasing when unlocking is attempted the spring 18 is provided exerting a slight upward pressure on the arm of the lever 3.

To attach the unitary device of this invention just described to the hanger of any carrier such as hanger 23 attached to the frame 20 and wheels 21 a circular hole is made in that hanger adapted to receive the curved face of the casting 1 and to be engaged by the flange 12, the casting being inserted through said opening in the member 23 until the flange 12 is in contact with said member 23. When in this position the frame 1 may be rotated within the member 23, to different angular positions corresponding to the angularity of the rope to which the jaws are attached thereby allowing the rope to pull the hanger 23 through the gripping jaws 1 and 3 without there being any danger of injuring the jaws due to the fact that the traction rope is not in line with the central axis of the jaws. In order to prevent the whole device dropping out of the hanger 23 any sort of a securing mechanism may be applied to the front of the casting 1, one form of which is here shown. This consists in applying two lugs 11 to opposite sides of the front of the main frame 1 and providing two corresponding sized and shaped openings 25 at the top and bottom of the opening in the member 23 in which the main frame 1 fits. In applying the mechanism to the hanger the frame 1 is rotated until the lugs 11 are in line with and slip through the openings 25 after which the frame 1 is rotated to its normal position with the result that the frame 1 and attached parts can not be removed until it is again rotated through ninety degrees from its normal position shown in the figures to the position in which the lugs 11 register with the openings 25. In other words a sort of a bay-

onet lock is provided by means of which the frame 1 may be inserted in the hanger 23 and afterward freely rotated.

In the operation of the device the operator first inserts the main frame 1 in the hanger 23 in the manner just described and moves the entire trolley with attached mechanism into approximate contact with the traveling traction rope 26 the jaws being open or in dotted line position of Fig. 3. He then moves the device along the track 22 until the roller 16 strikes the switch not shown, provided for the purpose which throws the lever 4 from the dotted line position of Fig. 3, to the full line position thereby gripping the jaws upon the rope 26 the jaws adjusting themselves against the action of the springs 19 in the manner described and the whole device adjusting itself to the angularity of the rope 26 with the hanger by rotating the entire mechanism within the hanger 23 in the manner described. When the trolley or bucket reaches its destination roller 16 now in the full line position of Fig. 2 engages an unlocking switch not shown, of ordinary construction which throws the lever 4 to the dotted line position of Fig. 3 thereby releasing the mechanism from the traction rope.

The claims are:

1. In a device of the class described, gripping jaws for a traction rope, a suitable supporting frame for said gripping jaws, a hanger for the object to be transported through the agency of said gripping jaws engaging said traction rope, providing journal bearings for the supporting frame engaging the hanger, and a pair of lugs on the opposite side of the supporting frame also engaging the hanger in all positions except one, in which position they are adapted to slip through openings in the hanger so that the supporting frame may be removed as described.

2. In mechanism of the class described, the combination of a suitable frame, two gripping jaws mounted opposite each other and adapted to engage each other, mechanism engaging one of said jaws capable of being swung to two different positions for the purpose of moving said jaw between open and closed position of the jaws, and yielding spring mechanism connected to the other jaw whereby said jaw may automatically adjust itself to varying sizes of rope.

3. In mechanism of the class described, the combination of a suitable framework, two oppositely disposed jaws pivotally mounted thereon, a lever mechanism for moving one of the jaws between different positions and a coil spring mounted in a suitable housing engaging the opposite jaw for the purpose of holding it adjustably in contact with the other jaw.

4. In a device of the class described, the combination of the main frame, gripping

jaws normally lying inside said main frame, pivotally mounted in operative position with reference to each other, hollow extension members upon said frame having coiled 5 springs therein engaging one of said jaws to adjustably hold it in position and a lever mechanism for operating the other jaw.

5. In mechanism of the class described the unitary mechanism comprising the combination of the cylindrical supporting frame 10 having the opening therethrough, the hollow housings 8 extending therefrom containing the springs 19 and a U shaped bolt therefor, the gripping jaws operatively mounted partly 15 within the supporting frame one jaw in operative relation with the springs 19 and the other in operative relation with a suitable operating and locking lever mechanism as and for the purposes set forth.

6. In a device of the class described, the 20 combination of a suitable frame, a pair of gripping jaws one pivotally mounted with reference to the other, an operating lever pivoted on the frame, a connecting link between the gripping jaw and the operating 25 lever, the pivotal points of connection between the lever, the link and the frame and between the link and the jaw being so located that they are in line with each other when the jaw is closed for the purposes set 30 forth.

In witness whereof, I have hereunto subscribed my name in the presence of two witnesses.

RUGELEY D. SEYMOUR.
